FAN BLADE

Kyle C. Whitefield, Springfield, Mass., assignor to
Westinghouse Electric & Manufacturing Com-
pany, East Pittsburgh, Pa., a corporation of
Pennsylvania

Application June 13, 1939, Serial No. 278,836

4 Claims. (Cl. 170—159)

My invention relates to air-circulating fans, and it has particular relation to an improved design of the blades, involving a new principle effecting an increase in the efficiency of the fan, while at the same time securing, in general, a reduction in the noise.

The principal object of my invention is to provide an open-air fan having a small number of blades, such as four, the surfaces of which correspond substantially to the surface of a sphere, or, more generally, an ellipsoid. Each fan-blade may be regarded as having been cut out of such a portion of the surface of the sphere or ellipsoid, and with such a shape, as to provide the desirable features respecting the acceleration of air in a direction parallel to the axis of the fan, as will be subsequently described; while the double curvature of the sphere or ellipsoid, in the axial direction, as well as in the peripheral direction, is advantageous in that the axial curvature may be utilized to offset the tendency of the air to move radially away from the fan-blades under the operation of centrifugal force.

My invention consists particularly in the blade-shapes, the fan-blade combinations, and the methods and systems, which are hereinafter described and claimed, and which are illustrated in the accompanying drawings, wherein:

Figure 1 is a front elevational view of one-half of a single-piece sheet metal fan-blade structure having four blades, the major portion of the surfaces of which conform substantially to the surface of a sphere,

Figs. 2, 3 and 4 are sectional views through different portions of the fan-blades shown in Fig. 1, the section-planes being indicated by the lines II—II, III—III, and IV—IV in Fig. 1.

Fig. 5 is a perspective view of a complete fan utilizing the form of blades shown in Figs. 1 to 4, and

Figs. 6 and 7 are front and side views, respectively, of a modified form of fan-blade structure utilizing separate blades which are riveted to a spider, the blade-surfaces in this case being of ellipsoidal type.

In Figure 1, the fan-blades are cut and stamped into shape, from a single piece of sheet-metal, so as to provide a hub-portion 10, and four blades 11, all of which are integrally joined together, with an annular strengthening-ridge or depression 12 in the hub-portion 10, and approximately radial, curved strengthening-ridges or depressions 13 extending out into the respective blades 11. Each of the blades 11 is dished into a shape corresponding substantially to the surface of a sphere

having a suitable radius R and a suitably located center, the center of the sphere for one of the blade-surfaces being indicated at 0 in Fig. 1. At the portions of the fan-blade structure where the blades merge into the hub-portion, as indicated at 16, the approximately spherical curvature is modified, so as to blend the flat and curved surfaces together without sharp angles or bends. The direction of rotation of the fan is assumed to be counterclockwise as viewed in Fig. 1, as indicated by the arrow.

Each of the fan-blades 11 may be regarded as having been cut from its spherical surface in such manner as to provide a forwardly curved leading-edge 17, extending out from the hub 10, and terminating in an extreme, forwardly projecting point 18 which is closer to the fan-periphery 19 than to the hub 10, that is, the radius of the point 18 is more than half of the radius of the periphery 19. As this forwardly projecting point 18 extends the farthest forward, around the surface of the imaginary sphere from which the blade-surface is assumed (for purposes of description) to have been cut, the blade-pitch in a peripheral direction is the smallest at this point 18 in the leading edge 17, as indicated approximately by the angle A in Fig. 4, although this angle A does not exactly represent the pitch in a peripheral direction, which would necessitate the cutting of a cylindrical cross-section through the blade 11 at the point 18, whereas Fig. 4 shows a cross-section cut by a plane surface which is indicated by the line IV—IV in Fig. 1.

It is desirable to have a minimum rate of acceleration of the air, in an axial direction, at this point 18 in the leading edge 17—which is to say, that it is desirable to have a minimum fan-blade pitch, in a peripheral direction, at this point 18 of the leading edge—because the peripheral speed is greater, here, than at other points in the leading edge which are closer to the hub—and since the peripheral speed is greater, a smaller entrance-angle or pitch of the blade is needed, in order to reduce the noise produced by the air-disturbance of the leading edge 17.

At portions beyond the region of the point 18, the leading edge 17 curves backwardly and merges gradually into the fan-periphery 19, so as to minimize disturbance of the air and to avoid going out too far forwardly, on the compound curvature of the sphere, so that the forward tip 18 of the fan-blade will not be curving too much in an axial plane.

Moving backwardly, along the fan-blade, from any point in the leading edge 17, and travelling

along the intercept of a cylindrical surface on the blade-surface, that is, keeping at a constant radius from the fan-axis 21, it will be seen that the blade-pitch, in this peripheral direction, increases at points removed back from the leading edge 17, so that, at the trailing edge 22, the air is given a strong forward acceleration in the axial direction, so as to increase the output of the fan, the trailing edge 22 being smoothly rounded off, so as to avoid excessive air-disturbance, which would result in noise.

The foregoing discussion considers the movement of an air-particle as it travels peripherally across the surface of the fan-blade, from the leading edge 17 to the corresponding radial point in the trailing edge 22, during the rotation of the fan. As previously intimated, however, the air-particles are subjected also to centrifugal forces tending to move them out in a radial direction, and it is because of this centrifugal tendency that my blades are designed with a curvature in a radial direction as well as in a peripheral direction, so that the outer portions of the blades curve inwardly, so as to direct the air back or in, toward the axis of the fan. The center 0 of the spherical surface of the illustrated blade is located closely enough in, toward the axis of rotation, 21, to provide the necessary rate of change of the blade-pitch in a radial direction as well as in the peripheral direction.

The coordinates of the center 0 are indicated at N and T in Fig. 1, and it will be seen that the center 0 is disposed at a radius, from the axis 21, which is less than the radius of the extreme forwardly projecting point 18 of the leading edge 17. The blade-pitch in a radial direction is substantially zero at the radius of the center 0, and hence at a radius which is less than the radius of the point 18 at which the peripheral blade-pitch is a minimum. At radii longer than the radius of the center 0, the blade-pitch in a radial direction increases on out to the extreme peripheral edge 19, at which point the air is given a strong impulse inwardly toward the axis, so as to operate in opposition to the centrifugal tendency of the air, due to the rotation of the blades.

While I have, thus far, specifically illustrated and explained my invention in relation to blade-surfaces which are parts of spherical surfaces, or surfaces of compound curvature in which the rate of curvature is the same, or uniform, in two planes at right angles to each other, it will be obvious that I am not limited to this uniformity of curvature. When the blades are being formed, or dished out, it is obvious that they may be given any desired form of compound curvature, such as is obtainable, in general, from any ellipsoidal type of surface.

In Figs. 6 and 7, I illustrate my invention, therefore, in a form utilizing blades 30 having ellipsoidal surfaces, the general principles of the design being the same, as already explained in connection with the spherical blades. In Figs. 6 and 7, also, each blade 30 is separately formed, and is attached to a spider 31 by any suitable means such as rivets 32, thus avoiding the limitations respecting the blade-pitch near the center of rotation, where the integral blade-construction shown in Fig. 1 required a merged blade-and-hub surface 16. This spider-construction, with separate blades, thus permits a very slight improvement in the blade-performance by improving the operation at points near the center of rotation, but the most important portion of the blade is the outer half thereof,

where the peripheral speed is greater, and it is most essential that the principles of my invention be more carefully observed in the outer portion of the blade surface, than in the inner portions thereof, which are closer to the center of rotation.

Tests have shown that my present invention effects a significant increase in the efficiency of the fan, or in the number of cubic feet of air, delivered by the fan, in proportion to the rate of power-consumption, or watts-energy required to drive the fan-blades. In general, also, my improved design results in a noticeable reduction in the noise of operation.

I claim as my invention:

1. A gas-circulating fan having a plurality of blades, at least the outer half of each blade having a surface which is substantially a predetermined portion of the surface of an ellipsoid, the curvatures of each ellipsoid being such, and said predetermined portion thereof being so shaped, and taken from such a part of the ellipsoid, that the blade-pitch in a peripheral direction is smallest at a point, in the leading edge, which is closer to the periphery than to the axis of the fan, the blade-pitch in a peripheral direction being larger at certain other leading-edge points than at said first-mentioned point, the blade-pitches in a peripheral direction increasing at points removed back from the leading edge, the blade-pitch in a radial direction being substantially zero at a radius less than the radius of said first-mentioned point in the leading edge, and increasing at greater radii so as to operate in opposition to the centrifugal tendency of the gaseous medium in which the fan operates.

2. A gas-circulating fan having four blades, at least the outer half of each blade having a surface which is substantially a predetermined portion of the surface of an ellipsoid, the curvatures of each ellipsoid being such, and said predetermined portion thereof being so shaped, and taken from such a part of the ellipsoid, that the blade-pitch in a peripheral direction is smallest at a point in the leading edge, which is closer to the periphery than to the axis of the fan, the blade-pitch in a peripheral direction being larger at certain other leading-edge points than at said first-mentioned point, the blade-pitches in a peripheral direction increasing at points removed back from the leading edge, the blade-pitch in a radial direction being substantially zero at a radius less than the radius of said first-mentioned point in the leading edge, and increasing at greater radii so as to operate in opposition to the centrifugal tendency of the gaseous medium in which the fan operates.

3. A gas-circulating fan having a plurality of blades, at least the outer half of each blade having a surface which is substantially a predetermined portion of the surface of a sphere, said predetermined portion being so shaped, and taken from such a part of its sphere, that the blade-pitch in a peripheral direction is smallest at a point, in the leading edge, which is closer to the periphery than to the axis of the fan, the blade-pitch in a peripheral direction being larger at certain other leading-edge points than at said first-mentioned point, the blade-pitches in a peripheral direction increasing at points removed back from the leading edge, the blade-pitch in a radial direction being substantially zero at a radius less than the radius of said first-mentioned point in the leading edge, and increasing at greater radii so as to operate in opposition to the cen-

trifugal tendency of the gaseous medium in which the fan operates.

4. A gas-circulating fan having four blades, at least the outer half of each blade having a surface which is substantially a predetermined portion of the surface of a sphere, said predetermined portion being so shaped, and taken from such a part of its sphere, that the blade-pitch in a peripheral direction is smallest at a point, in the leading edge, which is closer to the periphery than to the axis of the fan, the blade-pitch in a

peripheral direction being larger at certain other leading-edge points than at said first-mentioned point, the blade-pitches in a peripheral direction increasing at points removed back from the leading edge, the blade-pitch in a radial direction being substantially zero at a radius less than the radius of said first-mentioned point in the leading edge, and increasing at greater radii so as to operate in opposition to the centrifugal tendency of the gaseous medium in which the fan operates.

KYLE C. WHITEFIELD.
